UNITED STATES PATENT OFFICE.

GEORGE MORSE GUILD, OF BOSTON, MASSACHUSETTS.

PIANO-FORTE.

SPECIFICATION forming part of Letters Patent No. 351,761, dated November 2, 1886.

Application filed February 17, 1886. Serial No. 192,180. (No model.)

To all whom it may concern:

Be it known that I, GEORGE MORSE GUILD, of Boston, in the county of Suffolk, of the Commonwealth of Massachusetts, have invented a new and useful Improvement in Piano-Fortes; and I do hereby declare the same to be described in the following specification and represented in the accompanying drawing, which is a perspective view of part of the metallic string-frame of a piano-forte, together with parts of its strings and their bridge provided with my invention, the nature of which is defined in the claims hereinafter presented. The said figure also shows part of the wooden frame to which the said string-frame is secured.

In such drawing, A denotes a part of the metallic frame for sustaining the strings S, B being a metallic bridge over which the said strings pass to and through the agraffes C, and 20 thence to the straining-pins D.

E is part of the wooden frame on which the iron frame A is fixed.

In practice it has been found when the bridge is integral with the metallic frame—that 25 is, cast in one piece therewith, as is usually the custom—that the strings on being struck by the hammers are productive of hard or metallic tones. In order to prevent such I have the metallic bridge in a separate piece from the 30 rest of the metallic frame, and interpose between the bridge and the said frame a yielding cushion of cloth, leather, vulcanized india-

rubber, or other proper material, and I fasten the bridge to the frame by screws or other means, if necessary, though the pressure of 35 the strings upon the bridge, however, will generally suffice to keep the bridge in place. In the drawing such cushion is shown at F. With it the metallic tones of the strings are overcome, and there results, when the strings 40 are struck by the hammers, remarkably soft and pleasant tones.

I claim—

1. The combination of the metallic string-frame and strings of a piano-forte, and the 45 straining-pins and the metallic bridge of such strings, with a yielding cushion arranged on the said frame, between it and the bridge, and having the bridge borne upon it (the said cushion) by the strings, all being substantially 50 as set forth.

2. The combination of the metallic string-frame and strings of a piano-forte, and the straining-pins, agraffes, and metallic bridge of such strings, with a yielding cushion ar- 55 ranged on the said frame, between it and the bridge, and having the latter borne upon it (the said cushion) by the strings, all being es- sentially as represented.

GEORGE MORSE GUILD.
